UNITED STATES PATENT OFFICE.

ARCHIBALD H. BRINTNELL, OF TORONTO, CANADA.

ROTARY ENGINE.

SPECIFICATION forming part of Letters Patent No. 476,868, dated June 14, 1892.

Application filed August 24, 1891. Serial No. 403,561. (No model.)

To all whom it may concern:

Be it known that I, ARCHIBALD H. BRINTNELL, of the city of Toronto, in the county of York, in the Province of Ontario, Canada, have invented certain new and useful Improvements in Rotary Engines, of which the following is a specification.

My invention relates to improvements in rotary engines; and the object of the invention is to design a simple, effective, and economically-acting engine.

Figure 1 is a vertical section of my rotary engine. Fig. 2 is a cross-section. Fig. 3 is a detail of a forked block. Fig. 4 is an inside view of the end of the casing, showing the cam-groove.

In the drawings like letters of reference indicate corresponding parts in the figures.

A is a cylindrical casing, B the end caps for the same, and C the pistons. The pistons C are located in recesses c, made in the central disk D, secured in position on the hub E, keyed to the shaft F.

G are friction-rollers secured on the ends of the spindles g, which are journaled in sleeves f, secured on the inner ends of the pistons C. The opposite end of the disk D has secured to it a thin disk D', which forms ends for the recesses c.

H are a series of radial slots made in the central block D at the end of the recesses c, and H' are similar slots made in the disk D' at the opposite end of the recess c. The slots H H' are wide enough to permit of the free radial movement of the sleeves f.

I is a cam-groove made in the interior of the end caps B and designed for the passage of the friction-rollers G, so as to adjust the pistons, as hereinafter described, during the revolution of the engine. It will be noticed that the lower sweeps of the cams I are concentric with the axle of the engine, while the upper sweeps are eccentric to the said axle. Consequently as the pistons revolve they are drawn in toward the center as they complete the upper portion of their revolution.

R is an adjustable plate the sides of which form the inner edge of the cam-groove I.

R' is an adjustable plate the lower edge of which forms the top of the outer curve of the cam-groove I.

The plates R and R' are adjustably secured to the ends B by screw-bolts r r', projecting through slots s s' in the ends B. In order to permit the adjustment of the plate R, through which the shaft F extends, I form an enlarged hole t in the plate R. As the cam-groove I is wider than the diameter of the friction-rollers g, and as the sleeves J rest against the inner and outer ends of the slots H H' when the piston is into its fullest extent and out to its fullest extent, respectively, it will be seen that the friction-rollers g will impinge against the lower edge of the plate R and the lower edge of the plate R' only as they travel around the cam-groove I. It will therefore be seen that the friction of the rollers of the cam-groove I will be materially reduced. It will also be understood that on account of the adjustability of the plate R and R' the radial movement of the pistons C may be adjusted to a nicety.

J is a curved block bolted at the upper end of the cylindrical casing and having its lower surface eccentric to the center of revolution. The block J has open ends j, as shown.

K is a packing-block secured in the recess k in the center of the block J.

L' is a screw-bolt, the threaded end of which extends into a female thread made in the top of the packing-block. The screw-bolt is designed to vertically adjust the packing-block. l' are spiral springs located between the top of the recess k and the top of the packing-block K.

L and M are the ports, which are located immediately above the inner ends of the open end j of the curved block J. L and M are connected by the pipes l and m to the four-way cock N'.

n is the inlet-pipe, connected at the top of the casing N of the cock N'

O is the exhaust-port, located at the bottom of the casing N.

The port p of the four-way cock N' is shown in the drawings opposite the inlet-pipe n and pipe M and the port q of the four-way cock is shown opposite the exhaust-port o and pipe l.

Q is a lever secured on the end of the spindle of the four-way cock and designed to turn the said cock. The lever Q is designed to

turn the four-way cock so as to either shut off the steam or water or reverse the motion of the engine by bringing the port *p* opposite the ends of the inlet-pipe *n* and pipe *l* and the port *q* opposite the ends of the pipe *M* and exhaust-port *O*.

P is a supplemental exhaust-port located at the bottom of the cylindrical casing *A*. This port may be utilized for the purpose of with-
10 drawing pebbles or foreign matter getting into the cylinder when the engine is used as a wa-
ter-motor; or, if necessary, it may be utilized for the purpose of an exhaust either when steam or water is used as the means of pro-
15 pulsion.

Having described the principal parts involved in my invention, I shall proceed to briefly describe the operation of my engine. As shown in Fig. 1, the four-way cock is set
20 so as the pistons will revolve in the direction indicated by arrow. It will be seen that the steam or water entering port *M* will be thrown directly against the piston or pistons located beneath the open end *j* and that each piston
25 as it comes to this part of its revolution will be immediately driven around by the pressure of the steam or water, so that practically the steam or water is always acting on a piston or pistons. It will also be seen that the
30 action of the steam or water will be maintained against each piston until it reaches the opposite open end of the curved block, at which point the piston is drawn in by the eccentric portion of the cam-grooves *I* until it reaches
35 the packing-block *K*, from which point the piston is again thrown out by the eccentric portion of the cam-grooves *I*, so that the steam will immediately commence to act on it. When the piston has reached the other end of the
40 curved block *J*, the cam-grooves *I* have thrown it out to its full extent, in which position it is maintained by the concentric portion of the

cam-grooves *I* until it reaches the open end of the curved block, as before described.

From this description it will be seen that I 45 provide a very effective and economic rotary engine or water-motor. As the pistons partially fill the space around the central disk, I secure economy in steam or water. In practice I make the pistons of sufficient number 50 and sufficiently large to fill about fifty per cent. of the space in the cylindrical casing in which they move. It will also be understood that on account of the peculiar construction adopted that there will be very little friction 55 caused in the revolution of my pistons. It may also be seen that my engine might be driven by compressed air or gas and work as effectively.

Among other advantages in my rotary en- 60 gine is that it may be reversed without any difficulty and is always in position to start immediately upon the steam or water being turned on. It may be also used as a meter.

What I claim as my invention is—

In combination, the central disk having radially-movable pistons, the cam for operating them, consisting of two plates arranged with their edges opposite and at a distance from each other, one of which extends around the 70 shaft and has an elongated opening for the shaft and the other of which is located above the shaft, the said plates being independently adjustable toward and from each other, the abutment *J*, having an opening extending 75 through it from top to bottom on each side of the central portion, the inlet and outlet opening on opposite sides of the central portion, and the adjustable packing in the central portion, substantially as described.

A. H. BRINTNELL.
